UNITED STATES PATENT OFFICE.

FELIX E. VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

SLUGGING-MACHINE.

1,114,943.

Specification of Letters Patent.

Patented Oct. 27, 1914.

Application filed October 21, 1912. Serial No. 726,906.

To all whom it may concern:

Be it known that I, FELIX E. VALOIS, a citizen of the United States, residing at Haverhill, county of Essex, State of Massachusetts, have invented a certain new and useful Improvement in Slugging-Machines, of which the following is a specification, reference being had therein to the accompanying drawings.

10 My present invention has to do with machines for setting slugs in boots and shoes by forcing the end of a wire into the leather and cutting it off on a level with the surface of the shoe to form the slug. Machines of this kind are well known in the art, being usually called slugging machines, and examples are illustrated in the patent to J. Albrecht, No. 547,946, dated October 15, 1895, and the patent to S. W. Robinson No. 20 325,274, dated Sept. 1, 1885.

The present invention has for its object particularly to provide feed grippers which shall seize the wire throughout the entire length of the gripping surface, to provide effective means for moving the grippers up after each down stroke, to provide such a construction of these and the related parts that they may be made strong and durable, and to provide means to prevent injury to the shoe in case the knives fail to sever the wire completely, as frequently occurs when the knives become dull or are slightly out of adjustment.

The foregoing objects are attained in the machine embodying my present invention, and the machine is simple and reliable, and not likely to become broken or deranged even in the hands of an unskilful operator. The machine is also so constructed that the action of the grippers may be observed by the operator, thereby making it easier for the operator to keep the machine in good order.

The invention will be fully understood from the following description taken in connection with the accompanying drawings and the novel features thereof are pointed out and clearly defined in the claims at the end of the specification.

50 Referring to the drawings Figure 1 is a front elevation of a machine embodying my present invention, the slug setting instrumentalities being in their highest position.

Fig. 2 is a vertical section of the parts shown in Fig. 1 with the slug setting instrumentalities in their lowest position. Fig. 3 is a section on line 3—3 Fig. 2. Fig. 4 is a view in perspective of one of the grippers.

In the drawings, the frame of the machine is designated 11, the vertically reciprocating pusher 12; the knives 13, 13, and the knife-actuating levers, 14, 14. These parts are, in general, of the old and well-known form, and therefore will not be described in detail. The wire A from which the slugs are made, passes down through a slotted or channeled tube or throat 15, called herein for convenience the feed tube. This tube is cut away on the sides to permit the serrated edges of the grippers 16 (see also Fig. 4) to contact with the wire in the central channel in the feed tube, and is of uniform cross-section throughout its entire length, except at the extreme lower end. The two grippers are each made with an inclined outside face *b*, which slopes outwardly toward the bottom of the gripper, and the pusher 12 is made with two corresponding inclined faces *c* which are parallel with the faces *b* on the grippers so that they contact with each other for substantially their entire length. The grippers thus constructed have, as will be seen from the drawings, no great or sudden variation in cross section as is the case with grippers having a notch in their outer surface, or a projecting member attached thereto. The only differences in the cross section of the grippers throughout their entire length are those due to the serrations and to the inclined outside face; the grippers are therefore better capable of withstanding unusual strain and the reliability of the machine is much increased.

It will be seen that when the pusher 12 descends, it will contact with the grippers and force them inwardly and into contact with the wire for the entire length of the gripping surfaces. The grippers are made as long as possible but are separate from the other parts and there is no rigid retracting member for them, with the consequent difficulties arising from the use of a rigid retracting member.

For the purpose of causing the grippers to move upwardly again after they have com-

pleted their downward movement, I provide two springs 17, 17, of any suitable form, there being one spring for each gripper. In the drawing I have shown a coiled spring having two legs or ends 171, 171, one of which engages a hole in the bottom of the gripper and the other of which engages a hole in the lower end of the member 18 in which the knives are guided.

10 The feed tube or throat 15 is of uniform cross-section throughout its entire length except for the small portion below the lower end of the grippers. There is therefore no weak spot in the feed tube so that it will not break even if the machine is improperly operated. This construction is rendered possible by the fact that the feed grippers are retracted by springs instead of by a rigid operating member, partly contained within 15 the feed tube. Furthermore the grippers are not cut away at any point throughout their length.

As the inclined surface on the pusher contacts with the corresponding inclined 20 surface on the gripper for substantially the entire length of the latter surface, the gripper cannot tilt toward the wire at the top and allow the wire to buckle in the space between the lower ends of the grippers. Furthermore the pressure to which the wire 25 is subjected by the grippers is substantially uniform throughout the length of the grippers. The member 18 in which the knives 14, 14 are guided is cut away below the cross 30 bar 25 on which the knife actuating levers 14, 14 are supported, as will be clearly seen in Fig. 1 and Fig. 3, the opening being designated *f*. This opening enables the operator 35 to observe the lower ends of the grippers 16 at the sides of the feed tube 15 and to clean or oil the parts if necessary. The knives 13, 13 which are adjustably mounted on the lower ends of the pivoted levers 14, 14 are operated by two cams 20 and 21. These two cams each have a long rest *d* 40 and *e* respectively, so that the knives 13, 13, will remain together for substantially the entire upstroke of the machine, opening just as the top of the up-stroke is reached. This 45 arrangement has an important result. In case the knives are dull or improperly adjusted so that they have not completely severed the wire, they will either break off the wire at the level of the heel, if the wire has been nearly severed, or will lift the shoe up 50 off the support, by which the operator will be warned that the wire has not been severed and that the knives are dull or improperly adjusted. In either case no harm to the 55 shoe results such as occurs where the knives open as soon as the cutting takes place in which case if the wire has not been severed, it is pulled down on the upstroke of the machine and is bent over and bedded into 60 the shoe on the next movement.

What I claim is:

1. In a slugging machine, the combination of a pair of wire grippers each having a serrated face for engagement with the wire and an inclined exterior face extending nearly the entire length of the gripper, a pusher having a reciprocating movement parallel with the wire and having corresponding inclined faces substantially parallel with the faces on the grippers and contacting therewith throughout the length of the inclined surfaces on the grippers and means for positively actuating said reciprocating pusher to cause it to contact with said grippers and actuate them positively to grip the wire and feed it into the work. 70

2. In a slugging machine, the combination with wire grippers having inclined surfaces, of a reciprocating member having inclined surfaces coöperating with the inclined surfaces of the grippers, said reciprocating member causing said grippers to grip and feed the wire during one movement of its reciprocation, and a spring acting on each gripper to move it back with said member 85 during the opposite movement of said reciprocation. 90

3. In a slugging machine, the combination of serrated grippers each having an inclined exterior surface, a reciprocating pusher having inclined surfaces coöperating with the inclined surfaces of the grippers, the movement of said pusher in one direction causing said grippers to grip the wire and move with it in said direction, and a spring acting on each gripper and moving it with said pusher in the opposite direction. 95

4. In a slugging machine, the combination with a feed tube of uniform cross-section 105 throughout substantially its entire length, of grippers slidable in slots in the said feed tube, a vertically reciprocating pusher actuating the grippers in one direction and springs acting directly on the grippers to 110 actuate them in the other direction. 115

5. In a slugging machine, the combination of a pusher reciprocating parallel with the wire to be fed and having inclined faces for engagement with grippers, a slotted feed tube having a bore of uniform cross section throughout nearly its entire length, a pair of grippers each having a serrated face engaging the wire to be fed through the slots in the feed tube and having an inclined face for engagement with the pusher, the only differences in cross section throughout the length of each gripper being those due to the serrations and to the said inclined face, and means for positively reciprocating said pusher to cause it to contact with the grippers and actuate them positively to grip the wire and feed it into the work. 120

6. The improved slugging machine comprising vertically reciprocating wire feed- 130

ing mechanism, knives to sever the wire on the surface of the work, and cams operating the said knives said cams being each provided with a rest whereby the knives remain in closed position during the upward stroke of the wire feeding mechanism.

7. The improved slugging machine comprising vertically reciprocating wire feeding mechanism, knives to sever the wire, and

actuating means for the said knives timed to hold the knives in closed position during the upstroke of the wire feeding mechanism.

In testimony whereof I affix my signature, in presence of two witnesses.

FELIX E. VALOIS.
